CLAIM

(21) Appl. No.: **29/513,475**

I claim, the ornamental design for a mirror for high frequency coil of magnetic resonance image device, as shown and described.

(22) Filed: **Dec. 31, 2014**

DESCRIPTION

(30) Foreign Application Priority Data

Jul. 2, 2014 (KR) 30-2014-0032559

FIG. 1 is a perspective view of a mirror for high frequency coil of magnetic resonance image device, showing my new design;

(51) **LOC (10) Cl.** **24-01**

FIG. 2 is a front view thereof;

(52) **U.S. Cl.**

FIG. 3 is a rear view thereof;

USPC **D24/158**

FIG. 4 is a side view thereof;

(58) **Field of Classification Search**

FIG. 5 is another side view thereof;

USPC D24/158–161, 185, 186; 378/4, 21–27,
378/38, 40, 102, 196–198; 600/410, 422

FIG. 6 is a top plan view thereof;

CPC A61B 5/05; A61B 5/055
See application file for complete search history.

FIG. 7 is a bottom plan view thereof;

(56) References Cited

FIG. 8 is another perspective view thereof in an alternate configuration;

U.S. PATENT DOCUMENTS

FIG. 9 is another perspective view thereof in an environment of use; and,

5,150,710 A * 9/1992 Hall et al. 600/422
8,073,526 B2 * 12/2011 Graham et al. 600/411
D686,324 S * 7/2013 Davis et al. D24/158

FIG. 10 is another perspective view thereof in an environment of use.

The broken lines in the drawing show unclaimed environment

only and form no part of the claimed design.
